By Roland C. Rehm ## UNITED STATES PATENT OFFICE

JOHN E. JOHNSON, OF CHICAGO, ILLINOIS, ASSIGNOR TO ADDRETOK CO., OF CHICAGO, ILLINOIS, A CORPORATION OF DELAWARE

DEVICE FOR RECORDING SALES TRANSACTIONS

Application filed February 15, 1929, Serial No. 340,066. Renewed March 26, 1932.

This invention relates to business transactions which involve the making of records or the like containing specific data relating, for example, to an individual involved in the transaction; and aims to provide improved means for expediting and increasing the reliability and accuracy of such transactions.

The invention may be readily understood by reference to one exemplification thereof as applied to retail merchandising and recording of retail sales transactions. Such exemplification of the invention is illustrated in the accompanying drawings, in which:

Fig. 1 is a perspective view of a hand held imprinting device having associated therewith one form of sales book and record for receiving data involved in sales transactions;

Fig. 2 is a vertical transverse section through the imprinting mechanism (the sales record having been removed for the sake of clarity) taken approximately on the line 2—2 of Fig. 4;

Fig. 3 is a plan view of the imprinting mechanism, the manipulating and supporting handles having been broken away to permit illustration on a larger scale;

Fig. 4 is a vertical section through the imprinting device, taken along the line 4—4 of Fig. 3;

Fig. 5 is a bottom plan view of the holder for holding the customer-carried token, taken along the line 5—5 of Fig. 4;

Fig. 6 is a detail sectional view of a device for ejecting a token from the holder, taken along the line 6—6 of Fig. 5;

Fig. 7 is a general view (details omitted) showing the relation of the parts at the instant of impression upon the sales record; and

Fig. 8 is a similar view showing the relation of the parts immediately after impression, such position being assumed automatically and without intervention of the operator.

In the present embodiment of the invention, the physical instrumentalities employed cooperate to record upon a record (such as a sales record) in an invariably legible form, certain data specific to the customer, such

as, for example, the customer's name, address, credit rating, et cetera. These co-operating instrumentalities comprise a printing plate or token of a size and shape convenient to be carried by the customer and bearing in legibly embossed printing characters the customer's name, address, et cetera; a sales or other record upon which the customer-data may be imprinted by the embossed characters on the token on as many copies as may be desired; an imprinting medium; and a device for associating the sales record and the token and impressing the latter upon the record sheet or sheets thereby to record the data from the token legibly and accurately.

The present embodiment of the invention avoids direct contact of the customer-token with the ink or other imprinting medium, whereby the token may be returned to the customer in unsoiled condition and the danger of soiling the customer's hands or gloves may be avoided.

The individually-carried token or imprinting element comprises in this instance a plate 10 (Fig. 5) of metal sufficiently ductile and malleable that it may be embossed (and re-embossed if need be to correct errors or to make changes) to provide in relief, clear and sharp printing characters 11, that is, characters which will print clearly and sharply. The obverse or intaglio side of the plate exhibits the characters in normal order so that the data may easily be read. The long sides of the plate or token carry reinforcement in the form of longitudinal ribs 12 and marginal finishing beads 13, the latter serving also to provide the plate with smooth rounded edges. The side edges of the plate being smooth, round, and free from sharp projections or indentations, wear upon the purse, pocket or clothing of the customer is minimized, so that the plate lends itself to convenient handling,—thereby preventing any reluctance on the part of customers to develop the habit of carrying the plate and using it in making purchases or transacting other business. The marginal reinforcement prevents bending of the relatively soft metal of the plate by much han-

dling and preserves it in the flat condition desirable when the plate is used to print upon a record. In this connection the embossed surface of the plate also supplies a certain longitudinal and transverse reinforcement against bending. The beads 12 extend approximately into the plane of the top surface of the embossed characters 11, thereby minimizing the wear on the faces of the characters to which they are subjected in the normal carrying and handling of the plate. The foregoing structural features adapt the plate to be continuously carried by a customer without damage or impairment of function as a printing plate.

The device for operatively associating the printing token and sales record and for making the impression is in this instance embodied in a light weight, compact, hand carried or hand held device which requires no fixed or other support for its use and particularly avoids the use of valuable counter or other supporting space in department stores and the like. Such device comprises a platen 14 having an integral supporting handle 15 projecting rearwardly thereof. The handle and platen sub-structure are in this instance made hollow to reduce weight. The platen is faced with a plate 16 of hard rubber or other slightly resilient material appropriate for platen purposes. In area the platen corresponds in size to the type area of the token. The depth or vertical height of the platen is such that it may be readily inserted under a sales record or group of sales records (if more than one copy be made) without the necessity for removing the record sheet or sheets from the sales book (see Fig. 1).

The printing token is in this instance removably held in an impression head comprising a holder 17 movably carried by the supporting handle 15 by means of a supporting structure 18 opposite and spaced from the platen and in this instance integral with the handle 15. The impression head is limited to vertical movement relative to the platen by a guide rod 19 passing through the hollow structure 18 and screwed into the back of holder 17 (see Fig. 4). The guide rod 19 and holder are prevented from rotation relative to the platen by a guide pin 20 carried by the guide rod 19 and travelling in slots 21 in opposite sides of the housing 18. A relatively weak spring 22 surrounding the guide rod and confined between the head 23 thereof and a supporting plate 24 normally maintains the impression head at a substantial distance above the platen (see Figs. 2, 4 and 8).

The lower face of the holder is marginally grooved as at 25 to receive the edge beading 13 of the printing token and is flat in its middle area 26 to provide a backing surface for the type area of the token. The token is

releasably held in and against the holder by the slightly resilient marginal flanges 27 which extend sufficiently under the edge bead 13 to support the token in the holder.

The holder is advantageously provided with an ejecting device in the form of a plunger 28 which assists in the convenient removal of a token from the holder. Plunger 28 is carried in a longitudinal bore in the holder and a portion thereof projects from the rear of the holder. A screw 29 whose end projects in a longitudinal recess or cut out portion 30 in the plunger limits the forward and backward travel of the plunger. To remove a token it is simply necessary to press the end of the plunger, whose engagement with the token causes it to project sufficiently beyond the forward end of the holder to permit it to be visibly grasped by the operator.

The holder is advantageously designed to assist in the insertion of the printing plate therein in correct position, that is, with the embossed characters out. The height of the printing characters 11 is such that if placed in contact with the backing surface 26 of the holder they would hold the beaded edge 13 sufficiently far out of the holder to lie beyond the engagement of the retaining flanges 27, and the printing plate would, therefore, not be supported thereby. In other words, the plate will only enter the holder when its intaglio side (that is, the side which exhibits the characters in their normal arrangement) is in engagement with the surface 26 of the holder.

The impression upon the sales record is in this instance made by a percussive movement of the impression head which insures a sharp and clear cut impression not only on the original record sheet but on all copies thereof. The present embodiment is also designed so that the pressure delivered to the record, i. e., the pressure of the printing plate upon the record is only of instantaneous duration, thus eliminating any opportunity for impairing the sharpness of the impression as might occur if the pressure were prolonged.

The aforesaid operation of the impression head is effected in this instance, by giving it a high velocity by means of compression springs 31 located inside the supporting structure 18. These springs operate through the medium of plungers 32 having stop collars 33 adjacent their lower ends against which the springs press and which serve to limit the downward travel of the plunger by engagement with the bottom 34 of the housing. The upper ends of the plungers are connected to plate 24. The springs are energized by an operating handle 35 having spaced arms 36 passing on opposite sides of the housing 18 and pivoted thereto by the pin 37. The extremity of the handle 35 is placed an appropriate distance from the supporting handle

15 to permit the two handles to be readily grasped by one hand not only for manipulation but for support of the device (see Fig. 1). The handles 15 and 35 are yieldingly held 5 apart by a torsion spring 38 located between them and limited in its separating action by the pin 39 passing through the housing 18 and engaging the arms 36. The handle is operatively connected with the springs 31 by devices in the form of pawls 40 pivoted to the 10 extremities of the arms 36 and engaging flat surfaces on the pin 20. Thus, downward depression of the handle 35 relative to the handle 15 raises the plunger 19 which, carrying 15 with it the holder 17, compresses the spring 31 whose upper ends bear against the top of the housing 18. The pawls 40 swing with the handle 35 about its pivot pin 37 and are designed to clear the pin 20 when the springs 20 31 have been sufficiently compressed, thus releasing the springs which impart their energy to the impression head. This transfer of energy is accomplished by the time the stop collars 33 engage the bottom of the housing 18, at which point the printing plate and its 25 holder are still a substantial distance above the platen. Nevertheless the kinetic energy thus imparted to the impression head carries it downwardly at a high velocity, compressing 30 spring 22 (which is a relatively weak spring), to deliver a percussive blow upon the sales record.

This sharp legible impression made by the percussive action at the impression head results not only from the force with which the printing plate is caused to strike the record but because of the character of the force. Because of the rapidity of the blow the resistance of the various record sheets and interleaved carbon sheets even to slight movement with the printing plate (brought about by inertia and the air cushion between the sheets) is effective to hold the portions of the sheets not actually embraced within the outlines of the type, out of any substantial contact with the inking or inked surfaces,—thereby limiting the inked impression exactly to the outline of the type and resulting in a sharp impression. The rapidity of the printing operation also contributes to the sharpness of outline of the printed characters because no opportunity is afforded for slight relative shifting of the elements involved in the operation to produce the blurred outlines 55 which characterize an impression made by a slow or prolonged pressure. Another characteristic of the percussive blow by which the impression is made, is that there is no possibility of manual interference with the operation of the elements in making the impression. Successive blows are not only uniform but the impression head is free to react under the forces developed on impact which cause it instantly to raise the printing plate from the record. This reactive move-

ment is rendered effective by the circumstance that the plungers 32 do not travel with the impression head to the point of impression, thus limiting the force of the impression simply to the kinetic energy of the impression head itself. Subsequent contact of the printing plate with the record is prevented by the action of the light spring 22 which, on the rebound of the impression head, carries and holds it a substantial distance above the record. This upward movement is arrested by engagement of the holder with plungers 32. In this position the records may readily be removed or inserted without danger of contact with the hereinafter described inking 80 means.

Uniformity and clarity of a given impression also depends on the adequate inertia (i. e., weight) of the platen and the supporting structure beneath it, rather than on the 85 rigidity of the entire structure. Obviously, however, the platen and the supporting structure directly beneath it should not be unduly flexible. In adding weight to or beneath the platen care must be taken not to concentrate 90 such a proportion of weight at this point as to unbalance the device and make it inconvenient to handle.

The character and force of the percussion may be substantially varied by the design of 95 the impression head, particularly its weight and distance of travel. Further variation may be effected by the degree of initial compression in the springs 31. By the latter means the velocity of the impression head 100 may be varied, the force of the blow depending also upon the mass of the moving parts.

The pawls 40, pivoted as they are at 41 to the extremities of the respective arms 36, permit the automatic resetting of the device. 105 Springs 42 carried by the arms 36 and connected with rearwardly projecting arms 43 on the pawls, allow the return of handle 35 without binding of the pawls against the pin 20. As or shortly before the handle 35 reaches the point of engagement with the pin 110 stop 39 the ends of the pawls 40 will have cleared the pins 20 and their springs 42 will cause them to snap under the pins to reset the device. 115

In the present case the supporting handle, structure 18 and platen support are integral and pressed in complementary halves, from sheet steel. The halves are secured together by transversely extending screws, thus providing a hollow light weight device but with 120 adequate strength and durability.

Ink supply means is herein represented by an inking sheet 44 in the form of a carbon paper strip (the upper surface of which is 125 uninked) mounted in a device 45 carried on the impression head. The device includes a receptacle 46 of tubular or cylindrical shape within which is carried in roll form a surplus or supply of carbon paper. The car-

bon paper strip is lead across the face of the holder 17 (inked side down) and held slightly spaced therefrom by guards 47 screwed to the back of the holder 17 and projecting slightly beyond the face of a printing token. 5 This spacing of the carbon strip facilitates the insertion and removal of printing plates. The end of the carbon paper is passed between contacting feeding rolls 48 and 49 whose surfaces are roughened or knurled to effect a feeding of the carbon strip. The upper roll is provided with knurled head 50 by means of which it may be turned. Thus the carbon paper may be advanced slightly as occasion requires to present a fresh inked surface and the projecting extremity of the used strip may be torn off from time to time.

Carried as it is with the impression head itself, the blow of the printing plate in making the impression is not so much against the 20 carbon strip as against the record sheet. This contributes to a sharp impression on the upper record sheet. The upper or uninked face of the carbon strip prevents direct contact of the printing token with the ink supply, thereby keeping the token free from ink and enabling its return to the customer in a clean condition after use. A mark or guide 51 on the impression head (to align with an appropriately located mark 52 on the sale record) may be provided to assist in properly locating the record on the platen.

Since the ink supply means is in this instance carried by the impression head, its mass 35 must be taken into consideration in determining the total moving mass necessary to produce the proper momentum or percussion. If a lighter ink supply device were employed, the loss of mass would be compensated for in the relatively heavier weight of the other parts of the impression head.

While adequate momentum of the impression head to produce a proper impression might be secured by increasing the energy 45 stored in the actuating springs (instead of adjusting the mass of the impression head), there are practical limitations to this where the device is to be manipulated by girls or women, as is the case, for example, in department stores. Increase in spring energy may be secured either by employing stronger springs or by increasing the closing travel of the handles 15 and 35 (i. e., their separation), but the gripping strength and the hand 55 span of the sales girl place rather close limits on both of these means for increasing momentum. The minimum rather than the average hand strength and hand size must be considered.

For the same reasons it is important that the total weight of the device be small; twenty-five ounces in the present embodiment. A light weight, easily held and operated device is highly desirable to secure cooperation of the sales girl to effect the economies

inherent in a consistent use of the device. Obviously the problem of securing lightness requires that the mass of the impression head be not increased to secure momentum which can be secured by increased travel or strength of the actuating springs within the limits of easy manipulation by the sales girl. 70

In completing a transaction, such as a retail sale, in a system wherein the customer carried token is employed, the clerk first inserts the token in the holder, the light weight of the device readily permits this to be done while holding the device in one hand and inserting the token with the other. Whereupon the sheets upon which the impression is to be made are inserted over the platen (the balance of the record book lying, for example, below the platen support (see Fig. 1)). The operation being completed the token may be immediately withdrawn and returned to the customer. 85

While the installation of the above described system whether for retail merchandising or for recording other transactions does not preclude the making of purchases 90 and recording of sales or other transactions (in the same sales books) without the use of the individual printing plate or token, the advantages both to the individual and to the organization employing the system resulting from the habitual use of the plate or token, are so great that the individuals will inevitably fully cooperate with the organization to effect the general and systematic use of the plates or tokens. From the 95 standpoint of a retail customer, for example, whose effective cooperation requires the carrying and use of such a token whenever purchases are made, the speed of completing a given transaction at once impresses the customer. Furthermore, the errors, delays and failures in delivery are avoided, as well as erroneous debits on the customer's charge account due to illegible or erroneous data 100 on the sales record (when entered in long-hand). Since the token is always returned to the customer in unsullied condition, the latter is not reluctant to carry and use it regularly. 105

From the standpoint of the organization such as a department store, the speed in completing a given sales transaction obviously is highly advantageous because a given sales person can complete a greater number of sales transactions; and the mental fatigue of securing and writing names and addresses of customers, is wholly eliminated. The outstanding advantage to the department store is, however, the avoidance of loss through illegible or erroneous data on the sales record. Loss from this source is wholly avoided by the use of such tokens. The illustrative device requires no permanent support and need occupy no valuable counter space, but can 110 115 120 125

readily be moved about as convenience requires.

A single token is capable of use in making purchases or transacting other business at a number of establishments. In such cases 5 each establishment may emboss on the token an individual, private symbol (represented by 53) which may serve to indicate the credit rating of the individual. Another establishment when extending credit to an individual already supplied elsewhere with a token, may add its individual credit symbol 10 54. Such symbol on the token may serve, if the management of a store so desire, to indicate to the employee (who is familiar with 15 the significance of the private symbols of the establishment) the fact that certain credit has been extended to the individual to whom the token has been issued. Moreover, 20 an establishment may advantageously place on the token a description (by means of appropriate symbols or code) of the individual to whom credit authorization has been extended. On the other hand, a given establishment may not extend such significance to its credit or descriptive symbols and may, on occasion, require proof of the 25 individual's identity, etc., in the usual manner or that the sale be approved by an official, regardless of the possession by the individual 30 of a token.

For convenience and for purposes of illustration, the individual carrying the token has been referred to as a customer; but it should be understood that the invention 35 is not limited to uses in which the individual occupies the status of a customer.

Obviously the invention is not limited to the details of the exemplification thereof 40 herein illustrated and described, since such details may be variously modified. Moreover, it is not indispensable that all features of the inventions be used conjointly, since various features may be advantageously employed (without others) in different practices 45 and combinations.

Having described one embodiment of my invention, I claim:

1. A device of the character described 50 comprising in combination a platen adapted to receive a plurality of record sheets and interleaved carbon sheets, a supporting handle projecting therefrom, an impression head movably supported opposite said platen and having means for removably holding a printing plate, an operating handle associated with said supporting handle and arranged relative thereto so that the two handles may be grasped together in a single hand, resilient means adapted to be energized by the operating handle for moving said impression head, a trip automatically actuated upon further movement of said operating handle for releasing said resilient means to cause the latter to impart a rapid movement 55

to said impression head independently of the operating handle to deliver a percussive blow to the record sheets upon said platen to imprint said printing plate thereon, a spring for automatically raising the impression head 70 above the platen immediately after impression, and a carbon paper feeding device associated with said impression head and operative to present fresh carbon paper for said impression head. 75

2. A device of the character described comprising in combination, a platen adapted to receive a plurality of record sheets and interleaved carbon sheets, a supporting handle projecting therefrom, an impression head movably supported opposite said platen and having means for removably holding a printing plate, a carbon paper feeding device associated with said impression head and carrying a roll of carbon paper, an operating handle associated with said supporting handle and arranged relative thereto so that the two handles may be grasped together in a single hand, resilient means adapted to be energized by the operating handle for 80 moving said impression head, and means for releasing said resilient means to cause the latter to impart a rapid movement to said impression head independently of the operating handle to deliver a percussive blow to 85 the record sheets upon said platen to imprint said printing plate thereon. 90

3. A device of the character described comprising in combination a platen adapted to receive a plurality of record sheets and interleaved carbon sheets, an impression head movably supported opposite said platen and having means for removably holding a printing plate, a carbon paper supply device having feeding rolls for drawing a sheet of carbon paper across the printing plate held in said impression head, an operating handle associated with said platen, actuating means controlled by said operating handle and including a compression spring arranged to be compressed by said operating handle and subsequently released thereby to impart a rapid movement to said impression head and thereby to cause the impression of the printing plate to be made by percussion upon the 100 record sheets on said platen, and means for automatically raising said impression head above the platen immediately after impression. 105

4. A device of the character described comprising in combination a platen adapted to support a record sheet, a supporting handle projecting therefrom, an impression head movably supported opposite said platen and having means for removably holding a printing plate, a carbon paper supply device including a holder for a roll of carbon paper and a feeding roll adapted to be turned to draw fresh carbon paper into alignment with said impression head, an operating handle 120

associated with said supporting handle and arranged relative thereto so that the two handles may be grasped together in a single hand, and actuating means controlled by said operating handle and including a compression spring for giving said impression head a rapid movement toward said platen so as to strike the record sheet upon the latter with a percussive blow so as to imprint the 10 printing plate thereon.

In testimony whereof, I have signed my name to this specification.

JOHN E. JOHNSON.
